CIRCULAR LOOM FOR WEAVING OF HOSE

Christian Christiansen, Lille Foren, V. Aker, near
Oslo, and Gustav Otto Karl Rüsch, Mandal,
Norway

Application June 3, 1946, Serial No. 674,091
In Norway October 27, 1943

Section 1, Public Law 690, August 8, 1946
Patent expires October 27, 1963

1 Claim. (Cl. 139—13)

1

The present invention relates to circular looms for weaving hoses or tubes in which the weaving takes place at the upper edge of a weaving ring, and in which the weft threads or yarns are pressed in between the warp threads by means of one or more pressing organs, or sectors, which rotate above the upper edge of the weaving ring. In order to weave hoses on such looms with the tightness demanded for high pressure hoses, it was previously necessary to load or tighten the warp threads to a high degree, and at the same time to tighten the weft threads to the utmost in order to draw the weaving tightly together. Further, it was necessary to twist both the warp threads and the weft threads very hard in order to prevent them from failing under the heavy load. All this involved the disadvantage that the hose became very hard and stiff, especially in wet condition.

The object of the present invention is to provide an improved circular loom by means of which it is possible to weave hoses which are tight even under very high pressure, and which at the same time are soft and flexible.

According to this invention, in addition to the sector, a further pressing organ, a so-called press finger, is also arranged on the sector carrier. This press finger comes into action at a point where the angle or opening between the warp threads induced by the sector carrier due to its form, is larger than at the point where the sector itself comes into action. The heddle action in this instance is similar to that commonly employed with circular looms, being similar, for example, to that described in U. S. Patent No. 2,353,387 to Duncan Edward Farmar Canney, dated July 11, 1944. The shifting of the heddles occurs with respect to the movement of the sector carrier so that the shifting is virtually completed before the trailing edge of the sector carrier leaves the shed, and the shedding is, in effect, completed by the movement of the trailing end of the sector carrier out of the shed. The press finger on each sector carrier will then press the warp threads firmly against the weft thread which is laid in by the preceding sector, the shifting of the heddles having taken place before the press finger comes into action, whereby the whole weft is made tighter. Further, the press finger will force the warp threads somewhat apart, so that the following sector will more easily bring the weft thread fully into the crossing point of the warp threads. By this means a much closer pressing together of all threads is obtained, and, as experience has shown,

the same tightness of the hose may be obtained with 20-30 per cent less twisting of both weft and warp threads than previously necessary. At the same time the load of all threads may be reduced up to 50 per cent. The weight of the hose can thus be reduced by about 10 per cent. Owing to the small load of the threads, the hose also becomes quite soft even in wet condition, and the lesser twisting of the threads has the effect that the hose, when becoming wet, swells and therefore becomes tight very quickly.

The press finger may be wedge shaped with a thickness considerably greater than the thickness of the sector and preferably made with a plane horizontal part with which it rests against the upper edge of the weaving ring.

The drawing shows an example of an embodiment of a sector carrier with sector and with a press finger according to the invention. Fig. 1 shows the sector carrier looking from above and Fig. 2 a side elevation looking from the side facing the weaving ring. Figure 3 shows diagrammatically the two thread systems together with the sector carrier with sectors and the weaving ring.

1 is the sector carrier on which is arranged the sector 2 and the press finger 3, both acting above the upper edge 4 of a usual weaving ring 5 which is shown in dotted lines.

30 The press finger 3 comes into action at a point where the angle or opening between the warp threads is larger than at the point where the sector 2 acts, owing to the fact that the plate of the sector carrier forces the uppermost and the lower warp threads from each other. The press finger is fastened to the sector carrier partly by the screw 6, partly by the screw 7 screwed into the sector, and has a part 8 which presses the shedded warp threads firmly against the weft threads previously laid in. This part 8 is, as shown in Fig. 2, considerably thicker than the sector and preferably made with a wedge formed section with a plane lower surface resting against or rotating immediately above the upper edge 4 of the weaving ring. 9 is a guard preventing the threads from catching the screw 6.

40 10 is the weft thread which is passed around guiding pins 11, around the tension controlling device 12 and over the roller or pin 13 to the weaving ring.

45 14 and 14' indicate the warp threads which are passed from the bobbins 15, 15' through the guides 16 over the guide rods 17 and 18 and through known heddles 19, 19' to the weaving ring 5, at the upper edge of which the weaving

takes place by laying in of the weft threads, the woven hose 24 being pulled, by known means, downward through the weaving ring and the tube 25 carrying the same. The guides 16 as well as the guide rods 17 and 18 are, in the known manner, bent in a circle concentric with the weaving ring. In order to tension the warp threads each thread, between the guide rods 17 and 18, is loaded with a weight 20 having a hook engaging the thread.

Each bobbin 22 with the weft thread 10 is mounted on a rotating sledge on which also the sector carrier 1 with the sector is arranged, as well as rods 23, 23' over which the warp threads pass and which are so arranged that they separate these threads from each other so that they pass the edge of the weaving ring at a comparatively large angle to each other.

We claim:

A circular loom for weaving hoses, comprising a weaving ring, means for conveying warp threads thereto, a sector carrier adapted to rotate about said ring, a sector mounted on said carrier for pressing a weft thread inwardly between the warp threads, a separate press finger having a greater thickness than said sector

mounted on said sector carrier and adapted to press the warp threads firmly against the weft thread previously laid in, the pressing surface of said finger being an arcuate section concentric with said weaving ring, and said finger having a plane bottom surface disposed immediately above the top edge of said weaving ring to firmly press the lowermost warp threads against the said top edge of the weaving ring.
